UNITED STATES PATENT OFFICE.

JOHN W. FITZGERALD, OF DETROIT, MICHIGAN, ASSIGNOR TO L. A. YOUNG INDUSTRIES, INC., OF DETROIT, MICHIGAN, A CORPORATION OF MICHIGAN.

CUSHION-SPRING.

1,333,801.

Specification of Letters Patent. Patented Mar. 16, 1920.

Application filed November 22, 1918. Serial No. 263,678.

To all whom it may concern:

Be it known that I, JOHN W. FITZGERALD, a citizen of the United States, residing at Detroit, county of Wayne, State of Michigan, have invented a new and useful Improvement in Cushion-Springs, of which the following is a specification.

This invention relates to spring fasteners or centralizers, and has for its object a structure for properly locating the coiled supporting springs of a spring cushion without actually fastening the coiled supporting springs to the cover. This is accomplished by the arrangement hereinafter described.

In the drawings,—

Figure 1 is a plan view of a fragmentary character, showing the cushion embodying my invention.

Fig. 2 shows one of the coiled supporting springs before it has been placed in position in the cushion.

Fig. 3 is a fragmentary section of the cushion showing how the springs are assembled into the cushion.

Fig. 3^A is a sectional detail of the cup.

Fig. 4 is a fragmentary plan view of a modified form.

Fig. 5 is a sectional detail showing the spring before it is placed in the cushion.

Fig. 6 is a fragmentary section of the cushion showing how the springs are assembled into the cushion.

Figs. 7 and 8 are details showing how the eye that is struck out of the centralizing cup serves to fasten the tying member to the casing of the cushion.

In a certain class of spring cushions it has been found desirable to put the springs under an initial compression as several advantages follow the use of this form of construction. It is the object of the present invention to provide members which can engage with one end of the coiled supporting springs to be utilized in connection with the tying member to bear against the end of the spring to compress it. It is a further object to provide a centralizing member that can be attached to the cover or casing of

the cushion to hold the coiled supporting spring in a given position to avoid lateral tipping. To this end I employ centralizing cups *a*. These are preferably fiber and have shallow flanges that serve to fit over the outside of the top or bottom coil of the

coiled supporting spring. The rebound check and dampener *b* is in the form of a stiff coiled spring of smaller diameter that can pass through the coiled supporting spring and serve to tie the top and bottom of the spring together. This in connection with the cups when assembled serves to compress the coiled supporting spring, as will be indicated by comparing Figs. 2 and 3. The ends of the rebound check are sharpened as at *c* and then turned over by a suitable instrument to form a hook *d*, which may be raised by distending the spring and then caused to penetrate the cover and the fiber washer, as indicated in the right hand of Fig. 3. This serves to tie the two centralizing members together. It also serves to impale the cups upon the cover. Hence the cups have a fixed relation with the cover and the cups are made to serve as centralizers to prevent the tipping of the springs.

In Figs. 4 to 8 inclusive a modified form is shown. Here the cup is shown with the flange on the inside of the spring instead of on the outside. The centralizing cup in this case is metal and its center is cut to form the prongs *e* that really form a gromet to fasten the cup to the cover or casing *f* when they are turned down upon the casing. One prong *g* may be turned over the end of the rebound check, as indicated in Fig. 6, to fasten the ends of the rebound check to the cover *f* and the cups *a*.

The employment of a rebound check and dampener in the form of a linear member passing through the coiled supporting spring from end to end is regarded as a separate matter of invention and is claimed in my co-pending application executed of even date with this. The present application is limited, as regards the claims, to the use of members that engage the ends of the coiled supporting springs to centralize or prevent undue tipping of the springs laterally.

What I claim is:

1. In a spring cushion, the combination of a coiled supporting spring, a cover for the cushion, and a cup fitting into the end of the spring to centralize the spring and fastened to the said cover, the members being arranged to cause the cup to bear against the end of the spring to compress the same.

2. In a spring cushion, a coiled support-

110

2

ing spring, a cup having a centralizing relation with respect to the end of the spring, a cover for the cushion and to which the cup is attached, and a tying member for pulling the cup and cover down upon the spring to compress the same.

3. In a spring cushion, a plurality of coiled supporting springs, a cover for the cushion resting thereon and cups each pro-

vided in the end of the spring to centralize the spring, the cups being secured to the under side of the cover, the members being arranged to pass the cups to bear against the end of the springs to compress the same.

In witness whereof I have hereunto set my 15 hand on the 15th day of November, 1918.

JOHN W. FITZGERALD.
